A. D. RAY

FILM CONTAINER

Filed Jan. 26, 1921

FIG. 1

FIG. 2

FIG. 3

Albert D. Ray
INVENTOR

BY
Fetherstonhaugh & Co.
ATTORNEY

UNITED STATES PATENT OFFICE.

ALBERT D. RAY, OF CLEVELAND, OHIO, ASSIGNOR TO EMANUEL MANDELBAUM, OF CLEVELAND, OHIO.

FILM CONTAINER.

Application filed January 26, 1921. Serial No. 440,219.

To all whom it may concern:

Be it known that I, ALBERT D. RAY, a citizen of the United States, residing at 2284 East 89th Street, in the city of Cleveland, 5 in the county of Cuyahoga and State of Ohio, have invented certain new and useful Improvements in Film Containers, of which the following is a specification.

My invention relates to improvements in 10 film containers and the object of the invention is to devise a very simple and cheap form of container, which may be thrown away after use if desired.

My invention consists of a central pindle, 15 a spool therefor, an annular band preferably flanged and made of stiff paper rolled into circular form with the ends of the bands overlapping and spaced apart to effect a passage between them, and circular end 20 plates provided with annular flanges designed to extend over the edges of the band, the overlapping portions of the band being preferably provided with a black felt double lining through which the film is designed 25 to be drawn, and the parts being otherwise arranged and constructed in detail as hereinafter more particularly explained.

Fig. 1, is a view of my film container.

Fig. 2, is a cross section on the line 2—2 30 Fig. 1.

Fig. 3, is a section on the line 3—3 Fig. 2.

In the drawings like letters of reference indicate corresponding parts in each figure.

1 is a central pindle and 2 is a spool. 4 is 35 an annular band, which overlaps from 4' to 4² through portion of its periphery, there being a space left between such overlapping portion. At 4² the overlap is fastened to the band but an opening is left for the passage 40 of the film. At 4', however, a straddle tab 5 is placed over the free edge of the band in order to hold it in place and also to keep out the light.

The band 4 is preferably provided with 45 side flanges 4³ to assist in keeping out the light.

At the exit or mouth at 4' I preferably provide strips of black felt 6 and 7, the piece

6 being fastened to the under side of the free end of the flap and the piece 7 to the 50 band.

8 and 9 are the disc or circular ends, and are provided with flanges 8' and 9' respectively to project over the band 4.

It will, of course, be understood that all 55 these parts are fitted closely together, and the band and the end discs are for the sake of cheapness made of paper and suitably fastened or cemented together.

The film 10 is wound on the spool in the 60 usual way and passes out at 4² between the overlapping portion of the band, the end of the film passing out between the pieces of black felt 6 and 7, which, as they fit closely on to the film, prevents any passage of light 65 on to the film.

In order to use the film the straddle tab may be pulled off with facility.

Such a film container, as I describe, is very simple and so cheap that it may be 70 thrown away after the film has been used.

What I claim as my invention is:

1. A film container comprising a substantially circular band forming the circumferential wall of the container, said band having the side edges thereof flanged inwardly, caps applied to the flanged edges of the band and a spool supported between said caps.

2. A film container comprising a substantially circular band forming the circumferential wall of the container and presenting overlapping end portions spaced apart to define an intervening outlet for the film, the opposing outlet forming surfaces of the strip being lined with a light excluding material and the side edges of the strip being flanged inwardly, end caps applied to and telescoping opposite edges of the strip, a pindle extending between said caps having reduced ends journalled in the caps and shoulder portions engaging the inner sides of the caps and a spool mounted on said pindle.

In testimony whereof I affix my signature.

ALBERT D. RAY.
